UNITED STATES PATENT OFFICE.

FRANK F. KNOTHE, OF RIDGEWOOD, NEW JERSEY, ASSIGNOR TO KNOTHE BROTHERS INC., OF NEW YORK, N. Y., A CORPORATION OF NEW YORK.

HOSE-SUPPORTER.

1,119,833.

Specification of Letters Patent.

Patented Dec. 8, 1914.

Application filed May 28, 1914. Serial No. 841,420.

To all whom it may concern:

Be it known that I, FRANK F. KNOTHE, a citizen of the United States, and a resident of Ridgewood, in the county of Bergen and State of New Jersey, have invented certain new and useful Improvements in Hose-Supporters, of which the following is a specification.

The object of my invention is to provide a simple and efficient hose-supporter or garter adapted to be readily applied and removed, and which may be easily adjusted to desired positions upon the leg, and will be comfortable and non-injurious to the wearer.

In a preferred embodiment of my invention I provide a web or strap upon which is slidably mounted a tubular cushion or pad, end portions of the web or strap extending beyond the ends of the cushion or pad and carrying hose fasteners at their ends, whereby adjustment between the cushion or pad and said web or strap may be readily made to enable the cushion or pad to fit snugly at the desired position against the leg.

My invention comprises novel details of improvement that will be more fully hereinafter set forth and then pointed out in the claims.

Reference is to be had to the accompanying drawings forming part hereof, wherein

Figure 1 is a perspective view illustrating my improved hose supporter or garter in use; Fig. 2 is a plan view of the supporter extended; Fig. 3 is an enlarged section on the line 3, 3, in Fig. 2; Fig. 4 is an enlarged detail section on the line 4, 4, in Fig. 2; Fig. 5 is an enlarged detail face view of a portion of the supporter, showing the cushion or pad ribbed longitudinally, Fig. 6 is a section on the line 6, 6, in Fig. 5; Fig. 7 is a fragmentary detail, enlarged, of a modified form of the cushion or pad, and Fig. 8 is a section on the line 8, 8, in Fig. 7.

Similar numerals of reference indicate corresponding parts in the several views.

The numeral 1 indicates a web or strap, which is preferably in the nature of elastic webbing, and the same is provided at its free ends with clasps or fasteners 2 of any suitable or desired construction for attachment to the hose 3. At 4 is indicated a cushion or pad mounted slidably upon web or strap 1 and adapted to fit snugly and comfortably against the leg of the wearer, as

illustrated in Fig. 1. As shown, the pad 4 is in tubular or hollow form movably mounted upon web or strap 1, so as to be freely adjustable relatively to the latter to bring the cushion or pad in desired position upon the leg. In Figs. 1 to 5 the cushion or pad 4 is shown comprising inner and outer strips 5, 7, of suitable material, such as fabric, leather or the like, having an inner padding or lining 6 of some suitable relatively soft material, such as canton flannel, the edges of the fabric 5 being shown folded on the inner side of the padding 6. The edges of strip or facing 7 are also shown folded. The folded edges of said parts 5, 7, are shown stitched together, at 8, in a longitudinal direction, whereby a relatively soft tubular cushion or pad is provided. The end portions of the parts 5 and 7 are shown turned inwardly, (Fig. 4) and respectively stitched together at 9. The web or strap 1 freely fits within the tubular cushion or pad so that the latter may be adjusted along the former, or vice versa. While the cushion or pad 4 may be of any suitable length, I find it convenient to make the same about one-third the length of the web or strap 1, so that the end portions of the web or strap may extend the desired length beyond the ends of the cushion or pad, whereby said end portions of the web or strap may be crossed at the front of the leg, enabling the fasteners at the two ends of web or strap 1 to be attached to the hose, whereby the supporter is maintained on the leg, as illustrated in Fig. 1.

While the inner face of the cushion or pad may be substantially smooth or in accordance with the surface of the material of which the part 5 is made, I may also provide the inner face of said part with one or more ribs, as shown at 10 in Figs. 5 and 6, which may be done by folding the material and stitching the fold through and through, as indicated at 11, Fig. 6, in the nature of a tuck, preferably in the longitudinal direction of the cushion or pad. Such projection or projections serve to aid in retaining the cushion or pad in position on the leg.

Instead of forming the cushion or pad in separate parts 5, 7, secured together, said cushion or pad may comprise a tube woven or knitted in a single piece, as illustrated in Figs. 7 and 8, and may contain the padding 6, which in all instances may, if desired, be

secured to the outer fabric by an adhesive, or stitches, or both.

In using my improved garter the cushion or pad 4 may be placed upon the leg at the 5 desired part, as at the upper back portion of the calf, and the projecting ends of the web or strap may be crossed over the front portion of the leg and the fastenings 2 attached to the hose, the fastener 2 of the 10 righthand portion of the web being attached to the hose on the lefthand side of the leg, and the fastener 2 of the lefthand portion of the web being attached to the hose on the righthand side of the leg, as 15 illustrated in Fig. 1, whereby the supporter or garter will be retained in position. An advantage is that the cushion or pad may be adjusted to any desired position around the rear or side portion of the leg, and the 20 fastenings 2 may be attached to opposite sides of the hose, in a simple and convenient manner, the crossing of the free end portions of the web or strap causing the garter to remain in set position.

25 While the cushion or pad 4 may be substantially straight throughout its edges, I prefer to shape the same in a somewhat concave direction along its upper and lower edges, as illustrated, whereby it will tend 30 the more snugly to conform to the shape or bulge of the calf of the leg.

My improved garter is simple and cheap to manufacture, may be readily used, is soft and pliable, avoids binding and undue constriction on the leg, and enables the use of narrow and stretchable elastic fabric that overcomes the tendency to bind and chafe, and which need not be very strong, since the pad receives sufficient contact with the 35 leg.

Having now described my invention what I claim is:—

1. A hose-supporter of the character described comprising a tubular cushion or pad 45 adapted to fit at the rear portion of a leg, and webbing extending freely from the end portions of the cushion or pad, said cushion

or pad slidably receiving said webbing, and fastening devices attached at the free ends of said webbing. 50

2. A hose-supporter of the character described comprising a tubular cushion or pad adapted to fit at the rear portion of a leg, and webbing extending from the end portion of the cushion or pad, said cushion or pad slidably receiving said webbing, and fastening devices attached at the free ends of said webbing, said cushion or pad having one or more ribs upon its wearing face. 55

3. A hose-supporter of the character described comprising a tubular cushion or pad having its opposite edges in substantially concave form and adapted to fit at the rear portion of a leg, and webbing extending freely from the end portions of the cushion or pad and provided with means for attachment to a hose said cushion or pad slidably receiving said webbing. 60

4. A hose-supporter of the character described comprising webbing having hose 70 fasteners at its free ends, and a tubular cushion or pad mounted slidably upon said webbing between said fasteners, said cushion or pad comprising parallel strips having their longitudinal edges folded inwardly 75 and stitched together.

5. A hose-supporter of the character described comprising webbing having hose-fasteners at its free ends, and a tubular cushion or pad mounted slidably upon said 80 webbing between said fasteners, said cushion or pad comprising parallel strips having their longitudinal edges folded inwardly and stitched together, one of said strips having a lining located between the strip 85 and its inwardly folded edges.

Signed at New York city, in the county of New York, and State of New York, this 27th day of May, A. D. 1914.

FRANK F. KNOTHE.
